DISPLAY RACK

Murray Federman, Clifton, N.J., assignor to Glamorene
Products Corporation, Clifton, N.J., a corporation of Delaware

Filed Oct. 13, 1967, Ser. No. 8,989

Term of patent 14 years

Int. Cl. D6—01

U.S. Cl. D80—10

FIG. 4.

FIG. 1.

FIG.5.

FIG.2.

FIG.3.

I claim:

The ornamental design for a display rack, as shown.
